UNITED STATES PATENT OFFICE

FREDERICK P. SMITH, OF GLASSBORO, NEW JERSEY, ASSIGNOR OF ONE-HALF TO JAMES N. PAFF, OF GLEN LAKE, NEW JERSEY

ATTACHMENT FOR GAS GOVERNORS

Application filed April 29, 1929. Serial No. 358,772.

My invention relates to a new and useful attachment for gas governors of the general type employed for controlling and regulating the flow of gas preliminary to its flow through 5 a conventional gas meter which is interposed between the source of supply and the point of use or consumption.

My invention further relates to an attachment for gas governors of this general character which, in addition to controlling and regulating the flow of gas to the desired volume is also adapted to stop the flow of gas entirely, when the consumption of the gas is partially or completely stopped, thereby 15 eliminating all danger of explosion due to an accumulation of unconsumed gas, and at the same time preventing waste of the gas.

My invention further relates to an attachment for gas governors of this character 20 which is equally adapted for use in conjunction with all kinds of gas meters and supply systems without necessitating any alteration of the construction or interfering with the operation of the same.

25 My invention further relates to a novel attachment embodying the novel and advantageous features of my invention which is adapted for installation on gas governors of future manufacture as well as on conventional gas governors already in actual use to 30 impart to the latter certain novel advantageous functions and attributes not heretofore possessed or accomplished thereby eliminating the necessity of totally discarding governors already installed and rendering 35 the advantages of my novel invention attainable at a minimum cost.

To the above ends my invention consists 40 of a casing having a gas inlet leading from a source of supply, and a gas outlet leading through a gas meter to a point of consumption, there being free communication between said inlet and outlet, a diaphragm transversely dividing said casing into upper and lower compartments, a pipe leading from the lower 45 of said compartments to the atmosphere, a fluid in said pipe for normally sealing said lower compartment from the atmosphere, a pipe leading from the upper of said compartments to the atmosphere and having

its lower free end juxtaposed to the free end of said first mentioned pipe, the fluid in said first mentioned pipe being adapted to be ejected therefrom by the increase of pressure in said lower compartment into the pipe 55 leading from said upper compartment to seal the latter from the atmosphere.

My invention further consists of an attachment embodying the foregoing advantageous features which is adapted to be installed upon governors of conventional construction already in actual use and operation.

My invention still further consists of various other novel features of construction and advantage all as hereinafter described 65 and claimed.

For the purpose of illustrating my invention I have shown in the accompanying drawings several forms thereof which are at present preferred by me, since the same have 70 been found in practice to give satisfactory and reliable results, although it is to be understood that the various instrumentalities of which my invention consists can be variously arranged and organized and that my invention is not limited to the precise arrangement and organization of the instrumentalities 75 as herein shown and described.

Figure 1, represents a vertical sectional view of a governor embodying my invention 80 certain parts being shown in elevation.

Figure 2, represents a fragmentary view, partly in section and partly in elevation of an attachment adapted to be installed on governors in actual present use to impart to the 85 latter the advantages possessed by the novel construction shown in Figure 1.

Figure 3, represents a view in elevation, showing another modification of my invention applied to a conventional governor already in use.

Figure 4, represents a fragmentary view partly in section and partly in elevation showing a modified form of the attachment 90 shown in Figure 3.

Figure 5, represents a fragmentary view 95 of the left hand portion of Figure 1, illustrating the use of another modification of my invention.

Referring to Figure 1 of the drawings 100

which illustrates a novel governor construction embodying my invention, and in which like reference characters indicate like parts, 1 designates the governor casing which is composed of the bottom 2 and the top 3, suitably secured or assembled as at 4. 5 designates a gas inlet leading from a source of supply (not shown) and 6 designates a gas outlet leading to a point of consumption through a conventional gas meter (not shown). 7 designates a cap secured to the outer walls of the inlet 5 and outlet 6 at 8. The inlet 5 is provided with a U-shaped extension 9 which is provided with the port 10 which is controlled by the valve 11 adjustably carried at one end of the lever 12 which is fulcrumed at 13, and the other end of which is pivoted to the bracket 14 at 15. The bottom wall of the U-shaped extension 9 of the inlet 5 is spaced from the juxtaposed wall of the cap 7 to form a channel 16 for the reception of foreign matter which may be carried by the gas passing through the port 10 and which may be precipitated therefrom due to a decrease in the velocity of the gas. 18 designates a diaphragm which is clamped between the bottom disc 19 carried by the bracket 14 and the upper disc 20 said discs being secured by the screw 21 or its equivalent. 23 designates a spring which extends upwardly through the air tight boss 24 and the tension of which is regulated by the set screw 25, said spring being adapted normally to urge the diaphragm 18 downwardly. The diaphragm 18 is flexible and lags at 26 to permit of upward and downward movement in a manner hereinafter described. 28 designates a cap like member which is secured to the casing 1 at 29, by threading or in any other suitable manner, and which is provided with the outlet 30 leading to the atmosphere. 31 designates a U-shaped tube the upper end 32 of which communicates with the lower compartment 33 formed below the diaphragm 18, while the other end 34 thereof is deflected downwardly as at 35. The tube 31 contains a predetermined quantity of mercury or other liquid 37 and is provided with the upper inlet 38 closed by the cap 39 and with a bottom drain outlet closed by the nut or plug 41. Within the cap 28 is another U-shaped tube 44 the upper end 45 of one limb of which communicates with the upper compartment 46 formed above the diaphragm 18, while the upper end of the other limb thereof is formed into a funnel 48. The tube 44 is provided with a bottom drain outlet which is closed by the nut or plug 50 and with the vent 51 which will be hereinafter further referred to.

The operation is as follows:—

When the valve 11 is in good working order, the gas flows through the inlet 5 and out through the outlet 6 to the point of consumption. If the consumption of the gas is

partly or completely stopped, the excess accumulation of gas in the compartment 33 raises the diaphragm 18, which in turn lowers the valve 11 to close the port 10 to shut off the gas supply automatically. When the pressure of the gas in the compartment 33 has been relieved due to a resumption of the consumption of the gas, the diaphragm 18 is lowered by the spring 23 and by the pressure of the atmosphere with which the compartment 46 above said diaphragm communicates, thereby raising the valve 11 to open the port 10 to permit the further flow of gas through the inlet 5 and the outlet 6, in the usual manner.

To take care of leaks or defects in the valve 11, it has heretofore been the practice to provide the compartment 33 with a safety valve arrangement which permitted the escape of gas accumulated in the compartment when the pressure reached a predetermined limit, thus guarding against the occurrence of explosions, (see Smith Patent No. 1,499,885, Gaunt et al. No. 1,626,581 and others). The disadvantage of this practice, which it is the primary object of my invention to remedy, resided in the fact that when the pressure of the gas in the compartment 33 was relieved (by the escape of the accumulated gas therein into the atmosphere) the diaphragm 18 was lowered (by the spring 23 and the pressure of the atmosphere) and the valve 11 raised, thereby fully opening the port 10 and permitting the free flow of gas into the compartment 33. This resulted in the rapid refilling of the compartment 33 with gas, which in turn escaped into the atmosphere whenever the pressure in said compartment reached the limit to which the device is adjusted.

By my construction (see left hand portion Fig. 1) when the pressure of the gas within the compartment 33 has reached the limit to which the device is adjusted, the mercury 37 is ejected from the tube 31 into the tube 44 thus sealing the latter and allowing the escape of the gas from the compartment 33 through the tube 31 to the atmosphere through the outlet 30. Due to the partial vacuum thus created in the compartment 46 (by the raising of the diaphragm 18 by the pressure of gas in the compartment 33) and by sealing the tube 44 to shut off the compartment 46 from the atmosphere, the diaphragm 18 is maintained in its upper position, thereby maintaining the valve 11 in its lower position to close the port 10. In this position of the parts the flow of gas into the compartment 33 is determined by the size of the leak in the valve 11, as compared with the flow of gas through the fully opened port 10 as would be the case were the diaphragm lowered and the valve 11 raised, as in the prior art constructions referred to.

Furthermore, in this condition of the parts,

and until the leak in the valve 11 shall have been repaired, there is free communication between the compartment 33 and the atmosphere, through the tube 31 and the outlet 30, and the gas that flows past the leaky valve 11 escapes into the atmosphere with no risk or danger of exposition and without the aid of any safety valve arrangements. Thus by providing the tubes 31 and 44 communicating with the compartments 33 and 46 respectively and by ejecting the mercury 37 from the tube 31 to the tube 44, I provide a vent for the compartment 33 to permit the escape of gas accumulated therein into the atmosphere, and I seal the compartment 46 from the atmosphere to maintain a partial vacuum which tends to retain the diaphragm 18 in its upper position and the valve 11 in its lower closing position, thus reducing the amount of gas flowing into the compartment 33 to the minimum amount flowing past a leaky valve 11 in lieu of the volume of gas which would normally flow through the port 10 when the latter is fully opened by the raising of the valve 11.

In order to guard against the undue and undesired sealing of the compartment 46 and the consequent permanent retention of the diaphragm 18 in its upper position and of valve 11 in its lower closing position, I provide the vent 51 in the tube 44. Thus if the gas pressure in the compartment 33 should become excessive, but not sufficiently so, to justify or warrant the permanent closing of the valve 11, and only a part of the mercury 37 is ejected into the tube 44, the compartment 46 is provided with communication with the atmosphere through the vent 51, so that, when the temporary congestion of the gas in the compartment 33 has been relieved, the diaphragm 18 may still be lowered to open the valve 11, and is not "locked" in its upper position. In other words, by the provision of the vent 51, it is necessary that all the mercury 37 should be ejected from the tube 31 to the tube 44 (which can take place only when the pressure in the compartment 33 is such as to warrant permanent closing of the valve 11) before the compartment 46 is shut off from the atmosphere to maintain the diaphragm 18 in its upper position and the valve 11 in its lower closing position.

The mercury 37 ejected into the tube 44 may be drained therefrom by removing the nut 50, and is then poured into the tube 31 through the top inlet 38, so that the same amount of mercury initially placed in the tube 31 can be used indefinitely. It is further understood that by controlling the volumetric capacity of the tubes 31 and 44 and the amount of mercury placed therein, the reaction of my novel governor can be regulated or adjusted to any desired degree of pressure within the compartment 33.

In Figure 2 I have illustrated a modified

form of the parts shown in Figure 1, wherein I employ a cap 53, (in lieu of the cap 28) which is carried by or secured to the boss or collar 54 which has the outlet 55 leading to the atmosphere and which is provided with the nipple 56 which may be threaded into the lower compartment 33 of a governor casing 1 of the construction seen in Figure 1 or its equivalent. In the cap 53 is the U-shaped tube 57 which is provided with the upper inlet closed by the plug 58 and which communicates with the nipple 56 leading to the compartment 33 as at 59. The tube 57 has a quantity of mercury 37 which serves to seal the compartment 33 in the manner hereinbefore described. 60 designates a tube which is connected at its lower end to the upper compartment 46 of a governor casing 1, and the upper end of which communicates with the tube 61 in the cap 53 at 63. In this construction when the pressure in the compartment 33 is excessive, the mercury 37 is ejected from the tube 57 into the bottom of the cap 53 to seal the lower end 64 of the tube 61, thereby maintaining a partial vacuum in the upper compartment 46 above the diaphragm 18, with which the lower end of the tube 60 communicates, to maintain said diaphragm in its upper raised position and the valve 11 in its lower closed position in the same manner as described in connection with Figure 1 and for the same purpose. The attachment shown in Figure 2 is adapted for installation upon governors already in actual use to impart thereto the advantageous features of the construction shown in Figure 1. In this construction, the clearance between the bottom end 64 of the tube 61 and the bottom 62 of the cap 53 serves the purpose served by the vent 51 in the construction shown in Figure 1 to prevent the undue or unwarranted sealing of the tube 61 and the compartment 46, when only a small amount of the mercury 37 is ejected from the tube 57 due to a slight temporary congestion of the gas in the compartment 33.

In Figure 3 I have illustrated a further modification of my invention, wherein I attach a tube 66 to the upper compartment 46 in the governor casing 1, said tube being provided with the U-shaped portion 67 which has the vent 68, the bottom drain plug 69 and the receiving funnel 70. 71 designates a tube connected to the outlet 72 leading from the lower compartment 33 of the casing 1, as at 73, said tube being provided with the U-shaped portion 74. The function and operation of this construction is substantially the same as that hereinbefore described in that the pressure in the lower compartment of the casing 1 ejects the mercury (not shown) from the tube 74 into the tube 67 to seal the upper compartment from the atmosphere, thereby to retain the diaphragm 18 (not shown) in its upper position and the valve 11 (not shown)

in its lower closing position. The vent 68 serves the same function hereinbefore described and need not be further dwelled upon.

5 In Figure 4 I have shown a modification of my invention combining the features of construction shown in Figures 1 and 3 wherein I employ the cap 78 which is carried by the boss or collar 79 having the outlet 80 leading to the atmosphere and which may be connected to the lower compartment 33 of the gas governor already in use, by the nipple 81, and to the upper compartment 46 of said governor through tube 66. The operation of this modification can be understood by reference to Figures 1 and 3.

In Figure 5 I have shown a fragmentary view of the left hand portion of Figure 1, provided with a further modified form of 20 my invention, wherein the tube 31 discharges its mercury into the cup 83 which is pivoted at 84 and which when weighted by the mercury discharged thereinto from the tube 31 is depressed to raise the stopper 85 to close 25 the bottom of the tube 86 the upper end 87 of which communicates with the upper chamber 46 of the casing 1, the function of this modification being identical with that heretofore described in connection with Figure 1.

30 In this construction the cup 83 is so adjusted that no closing of the tube 86 takes place until the entire amount of mercury 37 shall have been ejected thereinto from the tube 31 thus guarding against undue sealing 35 of the compartment 46 in the same manner as described in connection with the vent 51 heretofore fully described.

I am aware that the invention may be embodied in other specific forms without departing 40 from the spirit or essential attributes thereof, and I therefore desire the present embodiment to be considered in all respects as illustrative and not restrictive, reference being had to the appended claims rather 45 than to the foregoing description to indicate the scope of the invention.

Having thus described my invention what I claim as new and desire to secure by Letters Patent, is:—

50 1. An attachment for a gas governor including a casing, a diaphragm therein dividing said casing into an upper compartment and a lower compartment, a valved inlet for said lower compartment, and an outlet for said lower compartment comprising, 55 a U-shaped outlet leading from said lower compartment to the atmosphere, a liquid in said U-shaped outlet normally sealing said lower compartment from the atmosphere, and 60 a second U-shaped outlet leading from said upper compartment to the atmosphere, the free end of said second U-shaped outlet being so positioned with reference to the free end of said first U-shaped outlet as to receive 65 the liquid ejected from the latter due to an

increase in pressure in said lower compartment to provide an outlet for said lower compartment and to seal said upper compartment from the atmosphere.

2. An attachment for a gas governor including a casing, a diaphragm therein dividing said casing into an upper compartment and a lower compartment, a valved inlet for said lower compartment, and an outlet for said lower compartment comprising, 70 a U-shaped outlet leading from said lower compartment to the atmosphere, a liquid in said U-shaped outlet normally sealing said lower compartment from the atmosphere, a second 75 U-shaped outlet leading from said upper compartment to the atmosphere, the free end of said second U-shaped outlet being so positioned with reference to the free end of said first U-shaped outlet as to receive the liquid ejected from the latter due to an increase in pressure in said lower compartment 80 to provide an outlet for said lower compartment and to seal said upper compartment from the atmosphere, and a vent for said second U-shaped outlet leading from said upper compartment to the atmosphere, the free end of said second U-shaped outlet being so positioned with reference to the free end of said first U-shaped outlet as to receive the liquid ejected from the latter due to an increase in pressure in said lower compartment 85 to provide an outlet for said lower compartment and to seal said upper compartment from the atmosphere, and a vent for said second U-shaped outlet to prevent the sealing of said upper compartment when only a portion of said liquid is ejected from said first U-shaped outlet.

3. An attachment for a gas governor including a casing, a movable diaphragm therein dividing said casing into two compartments, a valved inlet for one of said compartments, and an outlet therefor, comprising a conduit leading from said compartment to the atmosphere, a fluid in said conduit, and a second conduit leading from the second of said compartments to the atmosphere, the fluid in said first conduit being adapted to be ejected into said second conduit when the pressure in said first compartment reaches a predetermined limit, to provide an outlet for said first compartment and to seal said second compartment from the atmosphere.

4. An attachment for a gas governor including a casing, a movable diaphragm therein dividing said casing into two compartments, a valved inlet for one of said compartments, and an outlet therefor, comprising a conduit leading from said compartments to the atmosphere, a fluid in said conduit, a second conduit leading from the second of said compartments to the atmosphere, the fluid in said first conduit being adapted to be ejected into said second conduit when the pressure in said first compartment reaches a predetermined limit, to provide an outlet for said first compartment and to seal said second compartment from the atmosphere, and a vent for said second conduit tube to prevent the sealing of said second compartment from the atmosphere when only a part of said liquid has been ejected from said first conduit.

5. An attachment for a gas governor including a casing, a diaphragm therein di-

viding said casing into an upper compartment and a lower compartment, a gas inlet and a gas outlet for said lower compartment, said diaphragm being adapted to be moved by the change of pressure in said compartments, and a valve for said gas inlet actuated by the movement of said diaphragm, comprising a conduit for said lower compartment leading to the atmosphere, a liquid in said conduit normally to seal said lower compartment from the atmosphere, a second conduit leading from said upper compartment to the atmosphere, said conduits being so arranged that an increase of pressure in said lower compartment will eject said liquid from said first conduit into said second conduit to provide a vent for said lower compartment and to seal said upper compartment from the atmosphere to prevent movement of said diaphragm.

6. An attachment for a gas governor including a casing, a movable diaphragm therein dividing said casing into an upper compartment and a lower compartment, a gas inlet and a gas outlet communicating with said lower compartment, and a valve for said inlet operated by said diaphragm, comprising a conduit leading from said lower compartment to the atmosphere, a liquid in said conduit normally to seal said lower compartment from the atmosphere, and a second conduit leading from said upper compartment to the atmosphere, the free end of said second conduit being positioned below the free end of said first conduit to receive the fluid ejected from said first conduit by an increase of gas pressure in said lower compartment.

7. An attachment for a gas governor including a casing, a movable diaphragm therein dividing said casing into an upper compartment and a lower compartment, a gas inlet and a gas outlet communicating with said lower compartment, and a valve for said inlet operated by said diaphragm, comprising a conduit leading from said lower compartment to the atmosphere, a liquid in said conduit normally to seal said lower compartment from the atmosphere, a second conduit leading from said upper compartment to the atmosphere, the free end of said second conduit being positioned below the free end of said first conduit to receive the fluid ejected from said first conduit by an increase of gas pressure in said lower compartment, and a vent for said second conduit intermediate said upper compartment and the free end of said conduit.

8. An attachment for a gas governor including a casing, a movable diaphragm therein dividing said casing into an upper compartment and a lower compartment, a gas inlet for said lower compartment, a valve for controlling said inlet operated by said diaphragm, and a gas outlet for said lower compartment, comprising a U-shaped tube hav-

ing one limb thereof communicating with said lower compartment and the other limb thereof leading to the atmosphere, a liquid in the bottom connecting portion of said U-shaped tube normally to seal said lower compartment from the atmosphere, and a second U-shaped tube having one limb thereof communicating with said upper compartment and the other limb thereof positioned below the free end of said first U-shaped tube, to receive the liquid ejected from said first U-shaped tube due to an increase of pressure in said lower compartment.

9. An attachment for a gas governor including a casing, a movable diaphragm therein dividing said casing into an upper compartment and a lower compartment, a gas inlet for said lower compartment, a valve for controlling said inlet operated by said diaphragm, and a gas outlet for said lower compartment, comprising a U-shaped tube having one limb thereof communicating with said lower compartment and the other limb thereof leading to the atmosphere, a liquid in the bottom connecting portion of said U-shaped tube normally to seal said lower compartment from the atmosphere, a second U-shaped tube having one limb thereof communicating with said upper compartment and the other limb thereof positioned below the free end of said first U-shaped tube, to receive the liquid ejected from said first U-shaped tube due to an increase of pressure in said lower compartment, and a vent for said second U-shaped tube positioned above the bottom connecting portion thereof.

10. An attachment for a gas governor including a casing, a diaphragm therein dividing said casing into an upper compartment and a lower compartment, said diaphragm being vertically movable with the change of pressure in said compartments, a gas inlet and a gas outlet for said lower compartment, and a valve for said inlet adapted to be actuated by the movement of said diaphragm, comprising a conduit leading from said lower compartment to the atmosphere, a liquid in said conduit normally to seal said lower compartment from the atmosphere, and a second conduit leading from said upper compartment to the atmosphere, the free end of said second conduit being adapted to be sealed when said liquid is ejected from said first conduit due to an increase of pressure in said lower compartment from the atmosphere and prevent the movement of said diaphragm.

11. An attachment for a gas governor including a casing, a diaphragm therein dividing said casing into an upper compartment and a lower compartment, said diaphragm being vertically movable with the change of pressure in said compartments, a gas inlet and a gas outlet for said lower compartment, and a valve for said inlet adapted to be actuated by the movement of said diaphragm,

comprising a conduit leading from said lower compartment to the atmosphere, a liquid in said conduit normally to seal said lower compartment from the atmosphere, a second conduit leading from said upper compartment to the atmosphere, the free end of said second conduit being adapted to be sealed when said liquid is ejected from said first conduit due to an increase of pressure in said lower compartment, to seal said upper compartment from the atmosphere and prevent the movement of said diaphragm, and means to prevent the sealing of said upper compartment when only a portion of said liquid is ejected from said first conduit.
